UNITED STATES PATENT OFFICE.

HENRY L. DOHERTY, OF NEW YORK, N. Y.

APPARATUS FOR COKING COAL AND PRODUCING GAS.

997,941.

Specification of Letters Patent. Patented July 11, 1911.

Original application filed June 22, 1909, Serial No. 503,733. Divided and this application filed June 22, 1909. Serial No. 503,734.

To all whom it may concern:

Be it known that I, HENRY L. DOHERTY, a citizen of the United States, residing at New York city, in the county of New York and State of New York, have invented new and useful Improvements in Apparatus for Coking Coal and Producing Gas, of which the following is a specification.

This invention relates to apparatus for coking coal and producing gas and, in particular, to that kind of such apparatus in which the coking of the coal is performed by the direct action of gas flame and the products of combustion from such flame and the gases from the quenching of the coke passed in contact with the finished coke.

The object of my invention is to provide an improved form of apparatus for carrying out the process of coking revealed and claimed in a co-pending application, Ser. No. 503,733, filed June 22nd, 1909.

In the drawings, Figure 1 is a vertical section through an oven or coking chamber of the apparatus, on the line A B of Fig. 4. Fig. 2 is an enlarged section of the top of the oven showing the details of the charging mechanism, the water jacket of the same, poke-holes, etc. Fig. 3 is a vertical section through the recuperator on the line C D of Fig. 4. Fig. 4 is a plan of the whole apparatus. Fig. 5 is a section through the water cooled-lever mechanism operating the charging cones on the line E F of Fig. 2, showing the blowing apparatus in elevation.

1, 1', 1'', 1''' are the individual ovens; 2 the recuperator; 3 the gas blower and exhauster; 4 the air blower; 5 and 6 are the engines or motors driving 3 and 4, respectively.

Each oven, 1, has a main coking chamber, 7, having a thick fire-brick wall, 8, built in a metallic shell, 9. The chamber, 7, is partly closed at the bottom by a hopper bottom, 10, below which is located the quenching chamber, 11. This chamber has a grate, 12, which is formed of metal shelves or plates running horizontally across the chamber 11 and supported by the shell 9, thereof. These shelves are set staggered so that they form a step-grate upon which the column of coke in the chamber, 7, is supported.

13 is the discharge chute of the oven having a gate, 14, raised by a rack, 15, and pinion, 15'. A hand-wheel, 16, operates the pinion 15.

Spray caps, 17, are inserted in the quenching chamber and are supplied with water from the pipes, 18, 18'. Burners, 19 and 19', are set into the walls, 8, of the carbonizing chamber at such an angle that the flames issuing from them are directed downward upon the latest charged coal on the top of the coke bed. These burners comprise an outer tube, 20, of fireclay, or some other highly refractory material, and an inner tube, 21. The inner tube is set into 20 in such a way as to leave an annular space between it and the wall of the tube 20. This annular space is connected to a gas distributing pipe, 22, by the short tube 23. The inner tubes 21—21' are connected to the air-distributing pipes 24—24'. Valves, 25 and 26, on the gas and air connections 21 and 23, serve to control the gas and air supply to the burners 19.

The passages 27—27' for withdrawing the gases formed in the oven are inserted in the oven at about the middle zone of the coke bed therein. These "off-take" pipes discharge into pipes, 28 and 28', which run along the front and back, respectively, of the group of ovens. These pipes 28 and 28' are cross-connected by the pipe 29, and connected with the recuperator by the pipe 30. The air-distributing pipes 24 and 24' are cross-connected by the pipe 31, and connected to the recuperator by the pipe 32. The gas-distributing pipes 22, 22' are cross-connected by the pipe 33 and connected to the discharge pipe 34 of the gas blower 3 by a pipe 35. Valves, 36 and 37, on 34 and 35, respectively, serve to regulate the pressure under which the gas is supplied to the pipe 35. Poke-holes, 38, permit of access to the interior of the oven for the purpose of barring down the coke therein, when necessary. Poke-holes, 39 and 40, fulfil the same office for the quenching chamber 11. A door, 41, permits of entrance to the interior of the oven for the purpose of making repairs or for the removal of such coke as may fall from the grate 12.

The charging apparatus on the top of each oven comprises, a coal hopper, 42, closed by a hopper-bottom, 43, and a cone, 44. Below 42 is an air chamber, 45, closed by a conical plug of fireclay, 46, properly supported.

Since the temperature in the upper part of 7 is very high, in the usual method of

2

operation, it is necessary to provide a water-cooled device to operate the cones 46 and 44. The device for this purpose which I show in the accompanying drawings consists of a hollow rod, 47, closed by a heavy cap, 48, which latter, affords a bearing surface for the cone 46. 44 and 46 are rigidly attached to 47. At the top, 47, is attached to a T-connection, 49, the ends of the horizontal passage, of which are carefully turned to form journals. These work in corresponding solid bearings, 50 and 51, in the connections 52 and 53, respectively, which, with the T-connection 54, form a yoke-shaped connection, which I will designate for the sake of brevity as 55. Stuffing boxes, 56 and 57, respectively, prevent leakage around the bearings 50 and 51. Inserted in 47 and reaching nearly to the bottom thereof is a water-pipe, 58. The upper end of this has an L-connection which is screwed on to a short horizontal nipple, 59, screwed into a bushing, 60, which is set into that end of the T-connection 49 which works in the bearing 50. In the arm 52 is a passage, 61, equal in diameter to the pipes 59 and 58. The hollow-rod 47 communicates through the end of the T, 49, which is journaled in 51 with the passage 62 in the piece 53. A bushing, 63, is set into that end of the T-connection, 54, which is attached to the piece 52. Into this bushing 63 is fastened a nipple, 64, which is joined by an L-shaped connection with the pipe 65. Connected with the T 54 is a pipe, 66, which is, in turn, connected with the journaled T, 67, and envelops the pipe 65. The journaled ends of 67 work in the solid bearings 68 and 69, which are borne by a bracket, 70, attached to the shell of the coal hopper 42. Connected with bearing 68 is a pipe, 71, having a valve, 72, and with 69 a waste-pipe, 73. By opening the valve 72, water flows through 71, 65, 51, 59 and 58 to the bottom of 47, cooling the caps 48, rises through 47, and passing through 62, 66, 67 escapes through 73. By this device I am able to support the cone 46 in the chamber 7 in spite of the high temperature therein.

Surrounding the air chamber 45 of the charging hopper is a gutter, 74. This is supplied with water by the pipe 75. An overflow, 76, connects with a gutter 77, which collects the overflow from all the water jackets and discharges through the waste pipe 78. Set into the bottom gutters 74 are the water-jackets 79 of the poke-hole casings 80. These latter are fastened water-tight into 79 at the bottom thereof and project to the top of 74. Brackets, 81, fastened firmly in the gutter 74 serve to furnish support to the parts 80. Caps, 82, fit loosely over 80 and dip deeply enough into the gutter 74 to provide a water seal slightly deeper

than the height of the water column corresponding to the pressure in the chamber 7. These poke-holes 80 are provided for the purpose of permitting the barring of the coke-bed from the top when such treatment becomes necessary and also to provide access to the burners 19 and 19'. Prior to removing the caps 82, the air and gas must be shut off from the burners by closing the valves provided for that purpose.

The recuperator comprises two chambers, 83 and 83', having thick walls, 84, built in a metal shell, 85. Small man-holes, 86, having covers, 86', are provided for furnishing access to the interior chambers 83 and 83' and to the air flues contained therein. These latter consist of vertical flues, 87, connected top and bottom to headers, 88-88' and 89, respectively. A partition wall, 90, separates the two chambers 83 and 83', communication between which is established by the flue 91, in 90. Headers, 88', are connected by vertical pipes, 92, to the cross-flue, 93, which latter is connected with blower 4, by the pipe 94. The blower 4 is in connection, through the pipe 95, with a source of products of combustion, such as the stack flue 96. The air inlet is through the pipe 97. Valves, 98 and 99, on 95 and 97, respectively, permit of a regulated proportion of flue gas to be admixed with the air drawn in by the blower 4 when desired. Headers, 88, are connected by the vertical pipes 103 with the cross-flues, 104.

The method of operating my apparatus is as follows:—Coarse cinder or coke is charged into the chamber 7 until a column of that material has been built up to the top of hopper 10. A fire is now kindled on the top of this bed of cinder, the door 41 being open and the exhauster 3 operating at a low speed. Coke is now gradually charged into the chamber 7, until a bed of ignited coke has been built up to a little above the level of the gas "off-takes" 27-27'. At first, owing to the thinness of the fuel bed, the gas drawn off by the exhauster consists of products of complete combustion, CO_2 and N_2 , and is an ordinary "flue gas". As the depth of the bed of coke increases, the character of the gas withdrawn from the chamber 7 changes, an increasing proportion of carbon monoxide taking the place of the carbon dioxide, originally present, and, the gas passing through the exhauster has become a fairly good producer gas. To prevent the gas reaching the exhauster-blower 3 while still at a high temperature, the air blower 4 is set in operation, the valve 100 on 32 being closed and 101 on pipe 102 open. When the gas discharging through the discharge-pipe 34 of the exhauster 3 has become a fairly good producer gas, the valve 37 on pipe 35 is opened and the valve 36 on 34 closed sufficiently to

cause a slight pressure on the gas in 35. The valves 23 and 23' are now opened and the gas issuing from the burners 19-19' ignited. The valve 101 is now closed, 100 5 opened and air gradually turned on at the burners by means of valves 26-26'. Coke is now charged into 7 until the bed has reached the level indicated in Fig. 1. As soon as the entire column of coke has been 10 brought up to a good heat, the door 41 is closed. The gas from the burners 19-19' passes down through the hot coke its water vapor and CO₂ being dissociated with the formation of hydrogen and carbon monoxid, 15 forming producer gas. The apparatus is now ready for the actual coking operation. Coal is charged into 7, and is immediately subjected to the heat of the flame from the gas burners 19 and 19'. The volatile matter of the coal is distilled, and this together with the combustion gases from 19 and 19' passes down through the coke, setting up reactions therewith, which dissociate the water vapor and CO₂ as above explained, and 20 "crack" the heavy hydrocarbon vapors of the distillation products into hydrocarbons of lower molecular weight, which are permanent gases. As the coal becomes coked, material is drawn out at the bottom of the 25 oven through chute 13, and the hot coke settles down through 10 onto the grate 12. Water is now turned in the spray nozzles 17, and falling on the hot coke is vaporized, the vapor passing up through the hotter 30 coke in 10 and in the lower portion of the fuel bed. As a result the vapor is more or less completely dissociated into hydrogen, carbon-dioxid and carbon monoxid. The 35 products of this reaction together with the gases formed in the upper part of 7 are drawn off to the recuperator 2 through 27 and 27' and the connecting pipes. Passing through 2 the hot gases give up the major portion of their sensible heat to the air passing through the air flues of the recuperator. Part of the gas is passed back to the burners 40 through the pipe 35, as already explained, while the excess, not needed in the coking of the coal, is conducted to a holder, or to a 45 furnace, or gas engine as may be desired. 50

By means of this apparatus I am able to coke coal according to the process revealed in my co-pending application Ser. No. 503,733, mentioned above. I am by this 55 invention able to exercise thorough control over the coking operation and can vary at will the character of the coke produced simply by varying the conditions in the ovens by easily operated adjustments without 60 making any change in my apparatus.

Having described my invention, what I claim is:-

1. In an apparatus for coking coal and producing gas, the combination of a coking 65 chamber, a gas-burner in the upper part of

said chamber, a quenching chamber, separate from, but in communication with, said coking chamber, and means in said quenching chamber for spraying water onto the coke in said chamber, substantially as described. 70

2. In an apparatus for coking coal and producing gas, the combination of a closed coking chamber and a plurality of burners in the upper part of said chamber, said burners having double concentric passages for the passage under pressure of air and combustible gas, respectively, and being adapted to project a flame of burning gas upon the charge in said chamber, the said burners having an inclination such that the flame from each burner will impinge upon the said charge at, substantially, the middle portion of the upper surface thereof, substantially as described. 75

3. In an apparatus for coking coal and producing gas, the combination of a closed coking chamber and a plurality of burners in the upper part of said chamber, said burners having concentric passages for the 80 passage under pressure of air and combustible gas, respectively, and being adapted to project a flame of burning gas upon the charge in said chamber, substantially as described. 90

4. In an apparatus for coking coal and producing gas, the combination of a coking chamber, a burner in the upper part of said chamber, said burner being adapted to project a flame of burning gas upon the surface 100 of the charge in said chamber, a passage connecting the gas passage of said burner with the said coking chamber, and a draft-producing-means interposed in said connecting passage, substantially as described. 105

5. In an apparatus for coking coal and producing gas, the combination of a coking chamber, means for charging coal into said coking chamber, a gas burner in the upper part of said chamber, gas off-takes communicating with, substantially, the middle portion of said chamber; a quenching chamber separate from said coking chamber, and a passage connecting said coking chamber with said quenching chamber, substantially as 110 described. 115

6. In an apparatus for coking coal and producing gas, the combination of a coking chamber; means for introducing coal into said coking chamber; a gas burner in the 120 upper part of said chamber; gas off-takes communicating with, substantially, the middle portion of said coking chamber; a quenching chamber separate from said coking chamber, said quenching chamber comprising an inclosing shell, a stepped-grate adapted to receive the coke discharged from the said coking chamber, a means for withdrawing coke from said quenching chamber, and a means for spraying water onto said 125 130

stepped-grate; and a passage connecting the said quenching chamber with said coking chamber, substantially as described.

7. In an apparatus for coking coal and producing gas; the combination of a coking chamber; means for introducing coal into said coking chamber; a plurality of gas burners in the upper part of said chamber; gas off-takes communicating with, substantially, the middle portion of said coking chamber; passages joining the gas passages of said burners with said gas off-takes; a quenching chamber separate from said coking chamber, said quenching chamber comprising an inclosing shell, a stepped-grate adapted to receive the coke discharged from said coking chamber, a means for withdrawing coke from said quenching chamber, and a means for spraying water onto said stepped-grate; and a passage connecting the said quenching chamber with said coking chamber, substantially as described.

8. In a coal-coking and gas-producing apparatus, the combination of a closed coking chamber; means for introducing coal into said chamber; a plurality of burners in said coking chamber, said burners having double concentric passages for the passage under pressure of air and combustible gas, respectively, and adapted to project a flame or burning gas upon the charge therein; and a recuperator adapted to heat the air supplied to said burners, substantially as described.

9. In a coal-coking and gas-producing apparatus, the combination of a coking chamber; means for charging coal into said chamber, a plurality of burners in the upper part of said chamber arranged around the periphery thereof and adapted to project a flame of burning gas upon the charge in said chamber; a recuperator for heating the air supplied to said burners; a quenching chamber in juxtaposition to said coking chamber; a passage connecting the said quenching chamber with the said coking chamber; and off-take passages for withdrawing the gas formed in said coking oven at, substantially, the middle portion of the bed of coke therein, substantially as described.

10. In a coal-coking and gas-producing apparatus, the combination of a coking chamber; means for charging coal into said chamber; a burner in the upper part of said chamber adapted to project a flame of burning gas upon the charge in said chamber; a recuperator having a passage for gas and separate passages for air; a passage connecting the gas-inlet passage of said recuperator with the said coking chamber at, substantially, the middle portion thereof; a passage connecting the gas discharge-passage of said recuperator with the gas passage of said burners; a draft-producing means inter-

posed in the last-mentioned passage; a passage connecting the air inlet passage of said recuperator with a draft producing means; and a passage connecting the air discharge-passage of said recuperator with the air passage of said burner; a quenching chamber in juxtaposition to said coking chamber; a passage connecting the said coking chamber and the said quenching chamber; means for quenching coke in said quenching chamber, and means for withdrawing coke from said quenching chamber, substantially as described.

11. In an apparatus for coking coal and producing gas, the combination of a coking chamber; said coking chamber having walls and a dome of refractory material inclosed in a metal shell, water-jacketed poke-holes in the dome of said coking chamber, and poke-holes in the walls of said chamber, a plurality of gas burners in the upper part of said coking chamber, arranged around the periphery thereof, and adapted to direct a flame of burning gas upon the top of the fuel bed in said chamber, gas passages in said burners, and air passages in said burners, pipes connecting the gas passages of said burners to a gas distributing pipe, and passages connecting the air passages of said burners to an air distributing pipe, valves on said connecting passages, gas off takes at substantially the middle of said chamber, and a hopper bottom; a coal charging means comprising a coal hopper, a movable plug adapted to close the bottom of said hopper, an air chamber located between said coal hopper and the top of said coking chamber, a movable plug of refractory material adapted to close the bottom of said air chamber, 95

lever mechanism and to the plugs thereto attached, a water pipe connected with that one of said bearings which supports that trunnion of said tubular member whose interior passage is in communication with the inclosed water pipe of said tubular member, a waste pipe connected to the other of said bearings and communicating with the interior of said tubular member through the interior passage of the trunnion supported by said bearing, a passage in one arm of said yoke connecting the inclosed water inlet-pipe of said tubular member with the water inlet-pipe of said vertical member through a connecting pipe in the interior of said horizontal member, a passage in the other arm of said yoke, connecting the interior passage of said tubular member with the interior passage of said vertical member through the interior passage of said horizontal member, whereby a flow of water may be established through the said lever mechanism and through the plugs adapted to close the bottoms of, respectively, the said coal hopper and the said air chamber; a coke-quenching means, located below the hopper-bottom of said coking chamber, comprising an inclosed quenching chamber, a stepped grate in said chamber adapted to receive the coke discharged from said coking chamber, water-spraying means in said chamber, adapted to spray water upon the coke on said grate, water pipes connected to said water-spraying means, valves on said water pipes, poke holes in the wall of said inclosed chamber, a man-hole in the wall of said chamber; a means for discharging coke from said inclosed quenching chamber, said coke-discharging means comprising, an inclined chute, a gate on said chute, a rack on said gate, a pinion gearing with said rack, and a hand wheel attached to the axle of said pinion; a recuperator, said recuperator comprising, a metal shell, a refractory lining in

said shell, a baffle wall dividing the chamber inclosed by said shell into two parts, a plurality of passages in said baffle wall establishing communication between the parts of said inclosed chamber, a passage connecting the gas off-takes of said coking chamber with the gas inlet-passage to one of the parts of said inclosed chamber of said recuperator, a passage connecting the gas outlet passage from the other of said chambers with a gas blower, a plurality of groups of vertical flues in the chambers of said recuperators, the flues of each group being connected to an upper header and a lower header, a connecting passage between the lower headers of cooperating groups of vertical flues in each chamber, pipe connections to each of said upper headers, a cross-connection connecting the said pipe-connections to the upper headers of that one of said recuperator chambers to which the gas-discharge-passage is connected; a pipe connecting said cross-connection to a draft producing means; a draft producing means, having suction connections to a source of combustion gases and to the atmosphere; regulating valves on said connections; a cross-connection connecting the said pipe-connections to the upper headers of the other of said recuperator chambers; a passage connecting the latter of said cross-connections with the air distributing-pipes of said coking chamber; and a passage connecting the discharge-pipe of said gas-blower with the gas distributing-pipes of said coking oven, all substantially as described.

Signed at New York city, in the county of New York and State of New York, this 18th day of June 1909.
